US0D1017049S

(12) **United States Design Patent** (10) Patent No.: **US D1,017,049 S**
(45) Date of Patent: ** Mar. 5, 2024

(54) **COMBINED WARNING DEVICE WITH FLEXIBLE ATTACHMENT**

(71) Applicant: **Flasher GmbH**, Graz (AT)

(72) Inventors: **Alexander Rech**, Graz (AT); **Ines Wöckl**, Graz (AT)

(73) Assignee: **Flasher GmbH**, Graz (AT)

(**) Term: **15 Years**

(21) Appl. No.: **35/514,960**

(22) Filed: **Apr. 28, 2022**

(80) **Hague Agreement Data**

Int. Filing Date: **Apr. 28, 2022**

Int. Reg. No.: **DM/222713**

Int. Reg. Date: **Apr. 28, 2022**

Int. Reg. Pub. Date: **Aug. 19, 2022**

(51) **LOC (14) Cl.** **24-02**

(52) **U.S. Cl.**

USPC **D24/186**

(58) **Field of Classification Search**

USPC D24/186, 167; D14/344, 218; D10/37,

(57) **CLAIM**

The ornamental design for a combined warning device with flexible attachment, as shown and described.

DESCRIPTION

1. Combined warning device with flexible attachment

1.1 : Right

1.2 : Back

1.3 : Top

1.4 : Front

1.5 : Left

1.6 : Bottom

1.7 : Perspective

1.1 side elevation view; 1.2 rear elevation view; 1.3 top plan view; 1.4 front elevation view; 1.5 side elevation view; 1.6 bottom plan view; 1.7 perspective view.

1 Claim, 7 Drawing Sheets
